COLLAR FOR OVERCOATS AND TOPCOATS

Samuel A. Beebe, New York, N. Y.

Application September 24, 1937, Serial No. 165,452

2 Claims. (Cl. 2—98)

This invention relates to new and useful improvements in collars for overcoats and topcoats; and it has for its object to provide the construction and design of a collar, adaptable principally for those coats, which are made of soft materials that can not hold a crease around the neck at the proper place, and which generally lose neck size by stretching.

An advantage of the collar, thus designed and constructed by me, is to the effect that said collar will keep a permanent crease around the neck without submitting it even to a tight pressing.

Furthermore, said collar has a true neck size for each individual size of garment, and the collar is made so that it cannot gain or lose in size.

In this connection, it may be noted that on other garments the collar usually has to be stretched on the outside and shrunk around the edge of the neck at pressing, whereas this collar, as constructed and designed by me, does not need tight pressing.

With the above and other objects in view, this invention consists of the novel features of construction, combination and arrangement of parts, hereinafter fully described, claimed and illustrated in the accompanying drawing, forming part of this application, and in which similar characters of reference indicate corresponding parts in all views, and in which:—

30 Figure 1 is a top plan view of an undercollar, cut in four pieces.

Figure 2 is a similar view, showing the said four pieces sewed together, with the seams pressed open.

35 Figure 3 is a top plan view, showing two pieces of collar canvas to be secured to the four pieces, shown in Figure 2.

Figure 4 is a top plan view of an open-crease undercollar, already canvassed; while

40 Figure 5 is a top elevational, somewhat perspective view, showing my improved collar completed, embodying top and undercollar.

In referring more particularly to the drawing, the successive steps in making my improved collar are, as follows—

The undercollar, which is of the same material, or cloth, as the undercollar garment, must be cut in four pieces, as indicated by the numerals 10, 11, 12 and 13 in Figure 1; these four pieces are next sewed together with the seams pressed open, as illustrated in Figure 2, which shows the undercollar seamed before the two piece canvas is stitched on each side of the dotted line 14 in Figure 2. The lower part of the collar canvas 15, shown in Figure 3, is then laid on even on the

dotted line, as shown at 14 in Figure 2. This lower part of the collar canvas is cut lengthwise. The upper part of the collar canvas, which is cut on the bias, and shown at 16 in Figure 3, is thereupon stitched down alongside the dotted line 14 in Figure 2, and the canvas is stitched on the three seams 17 through the cloth, as shown in Figure 4; this forms an open-crease undercollar, already canvassed, as thus shown in said Figure 4.

As the next step, pad undercollar top and bottom and mark around with shaper to neck size; then trim around edges at marks, and sew the top collar, which is correctly cut to size, around edges of undercollar, and turn over, which thus completes top and undercollar, as shown in Figure 5. 15

As hereinbefore stated, the lower part of the canvas 15 is cut lengthwise in order to keep the neck portion from stretching, while the upper part 16 is cut on the bias in order to "give" according to the necessary size; these features are very important in the construction of this kind of collar.

The completed collar carries a permanent crease and cannot be creased in any other place. Inasmuch as the size is cut true at the crease, and the place of the crease cannot be changed, the size will always remain true, and the collar will always hug and fit the neck properly, as long as the garment lasts.

It is obvious that slight changes may be made in the construction, combination and arrangement of parts within the scope of the appended claims, without departing from the spirit of my invention, and I do not, therefore, wish to limit myself to the very exact construction shown and described herein. 30

What I claim as new and desire to secure by Letters Patent of the United States, is:—

1. A collar comprising, as a basis, an undercollar cut in four pieces, said pieces being sewed together and the seams pressed open, a piece of 40 collar canvas of a predetermined size, lengthwise cut, and disposed on top of said undercollar evenly, on a prefixed line, a second piece of collar canvas of a predetermined size, cut on the bias and secured to the undercollar along said pre-45 fixed line, said canvas being stitched on the seams through the cloth, whereby to form an open-crease canvassed undercollar, a padding arranged on said undercollar at the top and bottom thereof, and a top collar secured to the undercollar, by 50 sewing the outside edges of the top collar and the undercollar together.

2. A collar comprising, as a basis, a member cut in a plurality of pieces, said pieces being sewed together, a piece of collar canvas cut 55

lengthwise and disposed on top of said member at the lower part of the latter, a second piece of collar canvas, cut on the bias and stitched to said member above the first said piece of canvas, said second piece of canvas being stitched through the cloth forming an open crease between the lower

portion of the canvas cut straight and the upper portion of canvas cut on the bias, and a top collar correctly cut to size and secured to the edges of the undercollar.

SAMUEL A. BEEBE. 5
